STOKER MECHANISM

Original Filed Jan. 23, 1935

UNITED STATES PATENT OFFICE

2,127,923

STOKER MECHANISM

Joseph B. MacKenzie, Erie, Pa., assignor, by
mesne assignments, to The Standard Stoker
Company, Inc., (1922), New York, N. Y., a cor-
poration of Delaware

Original application January 23, 1935, Serial No.
3,058, now Patent No. 2,072,821, dated March
2, 1937. Divided and this application January
28, 1937, Serial No. 122,724

6 Claims. (Cl. 198—15)

This invention relates generally to stokers for locomotive boilers and more particularly relates to the fuel conveying system employed in a stoker mechanism.

5 It is the principal object of this invention to provide an improved conveyor for a stoker mechanism comprising a universal joint between a pair of conduit sections having a hinged portion affording access to the interior of the conduit sections.

10 More specifically, it is an object of this invention to provide a novel flexible joint structure for a locomotive stoker conveying mechanism, such flexible joint structure being disposed beneath the firing deck of the locomotive and tender and comprising a conduit portion hinged to a main conduit portion above the universal connection between a pair of conveyor screws operating within the stoker conduits, the arrangement of parts being such that upon swinging the hinged portion away from the main conduit portion, the universal joint between the conveyor screws is exposed and made accessible from above the firing deck.

15 A still further object of this invention resides in the provision, in the structure referred to above, of a clamp which forms a part of the flexible joint between a pair of stoker conduits and also functions to maintain the hinged portion of one conduit to the main portion thereof.

20 These and other objects will become apparent as the description of this invention is read in connection with the accompanying drawing, in which,

25 Fig. 1 is a central longitudinal vertical sectional view through the rearward portion of a locomotive and the forward portion of its tender illustrating the invention applied thereto partly in similar section and partly in elevation;

30 Fig. 2 is a plan view of the forward end of the stoker of the invention with the firebox back-head shown in section;

35 Fig. 3 is a sectional view taken on the line 3—3 of Fig. 1;

40 Fig. 4 is an enlarged view in elevation of the forward end portion of the movable conduit section provided with the hinged cover at the universal joint; and

45 Fig. 5 is a transverse sectional view taken on the line 5—5 of Fig. 1, showing the spherical seat-like support for the movable conduit section.

50 Referring to the drawing, the locomotive 10 is provided with a boiler firebox 11, having the grate 12, a backhead 13, and a cab 14 having the

deck or floor 15. The backhead is provided with the vertically elongated firing opening 18 extending above and below the cab deck 15 and spaced above the mud ring 19.

5 Rearward of the locomotive 10 the tender is indicated at 20. It is of ordinary construction having the frame 21, the fuel bunker 22, and the deck or floor 23 which carries the usual slide plates 24. These slide plates control the flow of the fuel from the fuel bunker into the stoker 10 S which is of novel construction and now will be described.

10 The stoker S includes a conveyor 25 leading forwardly from the tender 20, and a fuel delivery conveyor 26 which receives fuel from the conveyor 25 and delivers it to a point above the grate 12 for distribution. Comprising the conveyor 25 is the open mouth trough 27 mounted beneath the tender deck 23 to receive fuel from the bunker 22 through a central aperture 29 in the deck 23, the size of this aperture being controlled by the shiftable plates 24. Extending forwardly from the trough 27 and rigid therewith is a tubular conduit 31 which terminates at its forward end beneath the locomotive cab deck 25 15 and has loosely telescoped over its forward end a sleeve-like conduit 32. At its forward end the latter conduit is provided with a spherical member 33 which is received in the spherical seat 34 of the fuel delivery conduit 35. A clamp 36 20 retains the spherical member 33 in its seat 34 to form a universal joint connection 37 between the fuel delivery conduit 35 and the sleeve-like conduit 32.

25 At the rear of the trough 27 and rigid therewith is a gear casing 38 which houses and maintains in an operative relation suitable gearing (not shown) for driving the stoker conveyors. Power is transmitted to such gearing from the motor 39 by flexible shafting 39a. Depending 30 from the under side of the gear casing 38 is a spherical member 40 which rests in a complementary seat 41 of the supporting bracket 42. By this arrangement, the conveyor 25, at the rearward end thereof, is mounted to pivot about 35 a vertical axis and also about a transverse horizontal axis. It will also be observed that the rearward end of the conveyor 25 is restrained against relative fore and aft movement with reference to the tender 20 by reason of the engagement of the spherical member 40 in the seat 41. Movement of the conveyor 25 about a longitudinally extending axis is prevented by providing the gear casing 38 with laterally projecting flanges 43, one at each side of the spherical 45 50 55

member 40, each flange 43 resting upon a rail 44 formed at each lateral extremity of the bracket 42 and having a convexly curved upper surface. By the described construction, together with the universal joint connection 37 and the telescopic sleeve-like conduit 32, it will be apparent that the necessary flexibility has been provided for the stoker conduits when the locomotive and tender are rounding curves or passing over switches, frogs and turntables.

The means for conveying fuel through the stoker includes a conveyor screw 45 having a portion thereof within the trough 27 and extending forwardly therefrom through the tubular conduit 31 to a point adjacent the universal connection 37 between the fuel delivery conduit 35 and the sleeve-like conduit 32. At its forward end, the conveyor screw 45 is provided with a jaw 46 which is connected to the jaw 47 of the fuel delivery screw 48 in the conduit 35 by means of pins 49 and a block 50 to form a universal joint 51 between the conveyor screws 45 and 48. The conveyor screw 45 is driven from its rearward end by the gearing within the gear casing 38 and conveys forwardly the fuel which falls into the trough 27 from the bunker 22, the fuel being urged against the teeth 52 of a crusher 53 and reduced to a size suitable for efficient firing. The crushed fuel is then conveyed forwardly by the conveyor screw 45 to the delivery conduit 35 where the screw 48 urges the fuel through the upwardly opening mouth 54 of the fuel delivery conduit 35 into the zone of action of the distributor member 55 which projects the fuel to all parts of the firebed.

Leading forwardly and upwardly from the spherical seat 34, the fuel delivery conduit 35 passes through the lower portion of the elongated firing opening 18 and thence curves upwardly so that its discharge mouth 54 opens upwardly into the firing opening 18.

Rearward of discharge mouth 54 is mounted the distributor member 55 arranged to issue blasts of pressure fluid toward the firebox through the orifices 69. A casing 71, formed with the conduit 35 extends above the mouth 54 and is provided with inspection openings 72 above the distributor member 55.

Above the casing 71 there is shown a portion of a conventional firedoor 75 which closes the upper portion of the elongated firing opening 18 against outside exposure. The openings at each side of the delivery conduit 35 in the lower portion of this firing opening are closed against rearward exposure by a pair of flanges 76, one extending laterally from each side of the conduit, forming also a means for securing the conduit 35 to the backhead 13 by bolts 77. A further support for the conduit 35 is afforded by providing it with foot pads 78 which are secured by bolts to a bracket 79 carried by the firebox backhead 13 and mud ring 19.

Fuel emerging from the upwardly opening mouth 54 is swept forwardly across a table 80 by the jets of pressure fluid issuing from the distributor member 55. The table 80 is supported by the conduit 35 and extends forwardly therefrom. The table 80 and the forward portion of the conduit 35 are protected from the intense heat within the firebox by the vertical grate 83.

At times it is necessary to disconnect the conveyor screw 45 and the fuel delivery screw 48, as for instance when the pins 49 or block 50 are worn to an extent that their replacement is es-

sential. This can be readily accomplished by an arrangement of parts which includes a removably hinged upper forward section 56 of the sleeve-like conduit 32, which section includes, as an integral part, a portion of the spherical member 53. The section 56 is hinged to the sleeve-like conduit 35 by means of a lug 57 which engages a bolt 58 passed through the spaced ears 59 of the conduit 32. Lateral movement of the section 56 with reference to the conduit 32 is prevented by providing a seat 60 in the edges of the conduit 32 which are contiguous to the edges of the section 56. The edges of the section 56 are received in the seat 60 and its lower portion extends below the horizontal medial plane of the conduit 32 whereby removal of the pins 49 is facilitated. Upward displacement of the section 56, under normal operating conditions, is prevented by the reason of the clamp 36 which is secured to the delivery conduit 35 over the section 56 and by providing this section with a rearwardly extending lug 61 on its upper side which fits beneath the ledge 62 of the conduit 32.

Whenever it is found that the conveyor screws 45 and 48 must be disconnected for any reason, the mechanic removes the bolts 63 which secure the clamp 36 to the delivery conduit 35 and raises the clamp through the opening 64 in the cab deck 15. The upper forward section 56 may then be swung rearwardly to a position as shown by the dot and dash lines in Fig. 4 whereby the pins 49 and the block 50 may be removed and replaced if found to be worn.

At times, foreign material such as track spikes or waste in the coal will work between the universal joint jaws 46, 47 and the block 50 so that articulation of the universal joint 51 becomes limited, thereby causing irregular operation of the conveyor screws. By removing the clamp 36 from its position over the hinged section 56, the fireman may swing the latter to a position above the cab deck 15. Upon so doing, the universal joint 51 is exposed and the foreign material removed therefrom in order to relieve the articulating surfaces of this joint. It will be apparent that this may be done from a position within the cab 14, thus enabling the engine crew to make necessary repairs or adjustments without loss of running time.

It will be apparent to those familiar with locomotive stokers that the universal joint structure according to this invention is highly useful in the railroad industry because it renders possible the convenient inspection and repair of the universal joint 51 from a position in the locomotive cab 14 and in a manner which does not require extensive dismantling of major parts of the stoker mechanism.

This application is a division of my co-pending application for patent, Serial No. 3,058, filed January 23, 1935, for improvements in Stoker, now Patent No. 2,072,821, dated March 2, 1937.

I claim:

1. The combination including a pair of conduits, a spherical seat formed in an end of one of said conduits, a spherical member formed at the adjacent end of the other of said conduits, said spherical member being received in the spherical seat of the first named conduit, a clamp detachably secured to said first named conduit over said spherical member to form a universal connection between said conduits, a conveyor screw in the first named conduit, a conveyor screw in the second named conduit, and a universal joint connecting said conveyor screws in approximate co-75

incidence with the universal connection between said conduits, a section of said spherical member being hinged to the second named conduit and arranged to be swung away from its operative position upon removal of said clamp.

2. The combination including a pair of conduits, a spherical seat formed in an end of one of said conduits, a spherical member formed at the adjacent end of the other of said conduits, 10 said spherical member being received in the spherical seat of the first named conduit, a clamp detachably secured to said first named conduit over said spherical member to form a universal connection between said conduits, a conveyor 15 screw in the first named conduit, a conveyor screw in the second named conduit, and a universal joint connecting said conveyor screws in approximate coincidence with the universal connection between said conduits, a section of said spherical 20 member being hinged to the second named conduit and arranged to be swung away from its operative position upon removal of said clamp, a portion of said section extending below the level of the center of said universal joint.

3. In combination, a floor, a conveying system having a portion thereof beneath said floor, said conveying system including a pair of conduits, a spherical seat formed in an end of one of said conduits, a spherical member formed at the adjacent end of the other of said conduits, said spherical member being received in the spherical seat of the first named conduit, a clamp detachably secured to said first named conduit over said spherical member to form a universal connection between said conduits, such universal connection being arranged with the greater part thereof beneath said floor, a conveyor screw in the first named conduit, a conveyor screw in the second named conduit, and a universal joint connecting said conveyor screws in approximate coincidence with the universal connection between said conduits, said floor being provided with an aperture over the universal connection between said conduits and through which aperture said clamp may be removed, a section of said spherical member being hinged to a second named conduit and arranged to be swung away from its operative position through the aperture of said floor upon removal of said clamp.

50 4. In combination, a floor, a conveying system having a portion thereof beneath said floor, said conveying system including a pair of conduits, a spherical seat formed in an end of one of said conduits, a spherical member formed at the adjacent end of the other of said conduits, said spherical member being received in the spherical seat of the first named conduit, a clamp detachably secured to said first named conduit over said spherical member to form a universal connection
55 between said conduits, such universal connection
60 enabling the conduits to be bent in any direction.

being arranged with the greater part thereof beneath said floor, a conveyor screw in the first named conduit, a conveyor screw in the second named conduit, and a universal joint connecting said conveyor screws in approximate coincidence with the universal connection between said conduits, said floor being provided with an aperture over the universal connection between said conduits and through which aperture said clamp may be removed, a section of said spherical member being hinged to the second named conduit and arranged to be swung away from its operative position through the aperture of said floor upon removal of said clamp, a portion of said section extending below the level of the center of said universal joint. 5 10 15

5. The combination including a pair of conduits, a spherical seat formed in an end of one of said conduits, a spherical member formed at the adjacent end of the other of said conduits, said spherical member being received in the spherical seat of the first named conduit, a clamp detachably secured to said first named conduit over said spherical member to form a universal connection between said conduits, a conveyor screw in the first named conduit, a conveyor screw in the second named conduit, a universal joint connecting said conveyor screws in approximate coincidence with the universal connection between said conduit, said spherical member including a removable section, and means for hinging such removable section to the second named conduit, said clamp cooperating with said means for maintaining said removable section in operative position. 20 25 30

6. In combination, a floor, a conveying system having a portion thereof beneath said floor, said conveying system including a pair of conduits, a spherical seat formed in an end of one of said conduits, a spherical member formed at the adjacent end of the other of said conduits, said spherical member being received in the spherical seat of the first named conduit, a clamp detachably secured to said first named conduit over said spherical member to form a universal connection between said conduits, such universal connection being arranged with the greater part thereof beneath said floor, a conveyor screw in the first named conduit, a conveyor screw in the second named conduit, a universal joint connecting said conveyor screws in approximate coincidence with the universal connection between said conduits, said floor being provided with an aperture over the universal connection between said conduits and through which aperture said clamp may be removed, said spherical member including a removable section, and means for hinging such removable section to the second named conduit, said clamp cooperating with said means for maintaining said removable section in operative position. 35 40 45 50 55

JOSEPH B. MACKENZIE.
